JAMES A. SPEED AND ARTHUR G. BROOKE RIDLEY, OF SAN FRANCISCO, CALIFORNIA.

CARBURETER.

1,255,062.

Specification of Letters Patent. Patented Jan. 29, 1918.

Application filed September 14, 1914. Serial No. 861,521.

To all whom it may concern:

Be it known that we, JAMES A. SPEED and ARTHUR GRAHAME BROOKE RIDLEY, citizens of the United States and Great Britain, respectively, and residents of San Francisco, in the county of San Francisco and State of California, have invented new and useful Improvements in Carbureters, of which the following is a specification.

10 Our invention relates to carbureters for supplying gaseous fuel to power engines, and especially to securing the proper mixture of gasified fuel with the proper air content to secure a most effective explosive mixture.

It has heretofore been customary in devices of this nature to vary the speed of the engine in accordance with the requirements of the devices being driven thereby and to 20 supply the gaseous fuel for the engine variable requirements at a varying rate, said variation usually being obtained by the suction of the engine. Difficulty is experienced, however, under this variable engine demand 25 in securing the proper variation in the supply of fuel and at the same time the proper variation in the flow of air so as to maintain the proper degree of richness of mixture during the running of the engine at different speeds. In our carbureter, we provide 30 means whereby a series of two or more ports are uncovered consecutively, a greater area or number being uncovered as the rate of demand increases, so that upon an increased 35 suction on the part of the engine, a mixture of the requisite richness is established with the increased quantity of air at the increased engine speed, with a greater degree of accuracy, and at an increased efficiency, 40 to that heretofore attainable.

Means are also provided for preventing damage through back firing, and means so that, upon a sudden demand on the part of the engine to increase its speed, there is 45 caused momentarily, a restraint upon the opening of the carbureter ports, said restraint being accompanied by a momentary increased suction. This we utilize for the purpose of slightly enriching the explosive 50 mixture at such times to aid the engine to more quickly accelerate. Immediately thereafter however, the parts of the carbureter assume their normal position of maximum efficiency during the period of increased flow of gaseous fuel to the engine 55 needs.

By referring to the accompanying figures, the construction and operation of our improved carbureter will be made clearer.

Similar letters refer to similar parts in the several figures:—

Figure 1 is a cross section through the carbureter on the line x x' of Fig. 2.

Fig. 2 is a plan view of our carbureter.

Fig. 3 is an enlarged section through the distributor plate or nozzle and its seat.

Fig. 4 is a plan view of the distributor plate or nozzle which is partly broken away showing its seat and the provision for engine operation when running idle at slow speeds.

Fig. 5 is a side view of the lever connections to the throttle control.

Fig. 6 is an end view of the lever connections to the throttle valve.

Fig. 7 is a section view of one of the needle valves showing the retaining spring.

Referring now to the figures:—

(a) is the carbureter body or principal part forming with the annular piece (b) and 80 conical piece (c) a chamber (d) which is supplied with liquid fuel, usually gasoline or distillate. Said fuel enters chamber (d) through connections d' or d'' , the one not in use being suitably plugged, and passes 85 by the valve (e), which until chamber (d) is filled to the requisite height, is held open by the weight of the float (f). A constant level (w) will thus be retained in the chamber (d). These parts are old and form no 90 part of our present invention.

The fuel from the chamber (d) will escape through the passage (g) into the chamber (g') and thence by the dash piston (h) which is made with a clearance w' around 95 the stem working therein, and so completely filling the space g , g'' , g''' . The chamber (d) is of a substantially annular form and extends as shown at (d''') and from thence fuel is fed through the valve ports and by 100 the adjustable needle valves i , i' , i'' into the passage ways j , j' and j'' which communicate with the passage way (k), forming at their entrance therewith, port openings. Mounted to freely move in said passage way (k) is the stem (l) provided with 105 the distributor disk or nozzle (m). This nozzle I prefer to make of disk form having passage ways with outlets as (m'') connected through the central stem portion, as 110 further described below, and by which the fuel is drawn from the several conduits (j'')

(j) (j') as it advances in an upward direction. Turned in the said stem (l) are annular passage ways (k') and leading from these into a clearance passage are holes (k''). Said clearance passage in turn communicates with the distributor plate or nozzle (m) through the passage way (m') and thence to its outlets (m''). The annular body (a) is formed with a passage way (n) and clearance openings n' into said passage way so that air has free access to the under-surface of the distributor plate or nozzle (m) and upon said plate being raised, the air may flow freely into the carbureting chamber (o) and thence by the conical valve (p) and secondary valve (p') into the engine manifold, not shown, but to be connected at (v). This valve (p) consists of the outer conical portion seating when closed 20 against the conical wall of (c), and the inner surface of (p) forms the outer space (q). This valve is formed with a central sleeve portion forming a guide, within the interior portion of the piece (c), for the 25 said valve. The guide portion of (p) I prefer to internally thread for receiving the seat for the ball (r) and the adjustable nut (p''), the latter for limiting the upward movement of the disk (m). The valve (p') 30 when in its lowest position permits a slight clearance space (q) between its conical surface and the inside conical surface of the valve (p) and is provided with a stop nut on the central portion of piece (c) to limit 35 its upward movement.

When the engine is started and a suction demand made upon the carburetor, the first effect will be the raising of the valve (p') and the closing of the space (q) followed immediately by the raising of the valve (p) from its seat against (c). The secondary valve p' descends to its lowest position when suction exists, leaving a small clearance space q between p and p' of such dimension 45 as to permit the passage of discharging gases, but not permitting the passage of flame in the event of back firing.

The gaseous fuel passes freely from the chamber (o) through the passage ways o' 50 and by the valve (p) when it is lifted into an open position by the suction of the engine. The movement upward of this valve is limited by the position of the ball joint (r) which upon being raised through the 55 rotation of the connecting lever r', by well known means, permits, upon the suction demand of the engine being sufficient, the rising of the valve (p), and by the suction or air pressure against the plate (m), the 60 rising of said plate (m) and stem (l) to an amount sufficient to admit the requisite air from the passage ways (n) into the chamber (o), and by the opening movement of (l), the ports j', j or j' or two or more 65 of them are uncovered and fuel is admitted

into the annular passage way k' and through the openings k'' and thence through the passage way m' and exit passages m'', thus supplying the requisite additional fuel to correspond with the increased quantity of air and 70 forming a gaseous fuel of the proper richness in the chamber (o) from which it passes through the openings o' and thence past the valve (p) into the engine manifold connected at (v), well known, but not shown. The connecting lever r' is mounted upon a spindle r'' which carries also a lever (s) with adjustable limit stops s' and s''. 75

The construction of this feature is shown more clearly in Figs. 5 and 6 in which r'' is the stem carrying the connections to the ball joint (r). Fitted upon this stem is the piece r'', carrying the lugs u' and u''. Mounted rigidly on the stem r'' is a pin adapted to engage against the lug u' as 80 shown for a right hand assembly of the carburetor parts, or against u'' for a left hand assembly of the carburetor parts, in the first case corresponding with a movement of the swinging lever (s) in one direction 85 to permit the opening of the throttle valve, and in the second case, corresponding with a movement of the lever (s) in the opposite direction to permit the opening of the throttle valve and vice versa. The limit screws 90 s' and s'' determine the limits to which the said throttle valve may be moved through the movement of the lever (s). The lever (s) is clamped about the split hub of the piece r''' by the clamp screw s''' when the 100 parts have been assembled in the desired position. This clamping of the lever (s) also clamps the split hub of the piece r''' and stem r''. Suitable connections are made with the lever (s) by which the stem (r'') 105 is rotated in one direction or the other according to the desire of the operator to increase or decrease the speed of the engine. The piece q' is clamped to the annular portion (c) by a clamp ring (t) and screw (t'). 110 The adjustable needle valves i, i' and i'' are held in adjusted position by friction of a spring (v') as shown in Fig. 7.

We provide a slot n'' in the seat on which the distributing piece or nozzle (m) rests 115 during periods of engine idling. This is clearly shown in Figs. 3 and 4, and feeding into said slot n'' is a passage for fuel n''' connecting with the lower fuel passage j''. It will thus be seen that air and liquid fuel will at periods of slow engine speed be drawn through said slot into the carbureting chamber (o) and provide the requisite explosive mixture for the slow 120 speed operation of the engine.

Suitable fluid supply connections are made at d' or d'' and a connection with an engine, such for example, as used in gasoline-propelled vehicles at (v). Connections under the control of the operator are made 130

to the lever (s) and the parts when in their zero position are as shown in Fig. 1. The float (f), if in a low position, keeps open the valve (e) until liquid fuel has entered 5 the chamber (d), d'' rising to a sufficient height as indicated at (w). The part m, l, h, will hold the ports of j'', j, j' closed or nearly so. The operation of our carbureter is as follows:—Upon the starting of the engine 10 the first operation is that of a slight rotation of the stem r'', thus releasing the ball joint (r) from the valve (p) and permitting the valve (p) upon any suction effort on the part of the engine to rise, thus 15 also releasing the plate m for movement when the suction against said plate will throw it into an upward position admitting the flow of air through n', n into the chamber (o) and simultaneously admitting the 20 discharge of fuel from the first of the ports from the pipes j'', j, j'. When this suction effort is first produced by the engine, and if it is produced suddenly, the piston (h) acts to retard the upward movement 25 of the plate (m) due to the closing of the ball valve (h') acting in the dash pot g', and thus, through the momentarily excessive suction in the chamber (o) a larger quantity of fuel is discharged through the 30 passage ways (m''), producing for the moment an increased richness of mixture for the engine starting or accelerating requirements; and this is followed by a reduction in said richness as the suction pressure in. 35 the chamber (o) falls, due to the further opening of the distributor plate or nozzle (m) as the piston (h) advances upward in its displacement chamber or dash pot (g'). The action of the dash pot is as 40 follows: Connected with the central portion of the plate (m) is the ball valve (h') such that upon the first upward movement thereof, the ball seats against the piece (h) thus closing the chamber (g') from connection 45 through (g'') to (g''') causing the chamber (g''') to therefore act as a vacuum chamber opposing upward movement of the piece (h) which is loosely mounted about the nozzle stem and in slidable en- 50 gagement with the dash pot walls. As liquid leaks by the piston and into the chamber (g'''), the restraining movement of the nozzle in its upward direction continues until it arrives at its final position. This restraint 55 is only momentary, for the purpose of enriching the mixture.

Upon a closing of the valve (p) by the rotation of the shaft (r'') and the downward movement of the ball (r) forcing the 60 valve (p) upon its seat and forcing the nozzle (m) downward, rapid movement of this nozzle is permitted in that the ball (h') leaves its seat upon the piece (h), permitting free communication between (g''') and (g'), thus permitting quick down-

ward movement of the nozzle, but allowing only a slow upward movement. The ball valve (h') is shown loosely connected into the nozzle stem and held therein by this small stem and ball top. The valve (p) is 70 the throttle valve for the engine.

It is obvious that as the valve p' is free to rise against the interior conical surface of (p) that the first effect of suction from the engine will be the rising of (p') and the 75 closing of the passage way (q), followed by the rising of (p) from the interior surface of (c). If at any time back firing occurs, the valve (p) is, by the expansion of gases due to said back firing, caused to quickly 80 seat on the part (c) and the valve (p') to be forced to its lowest position clearing the passage way (q) through which the exploded and expanding gases find passage after passing through the clearance passages 85 q'', which passages may be formed by drilling holes into that portion of valve (p), or casting the conical part of valve (p) with arms projecting from its central inner portion. The passage q is of a small cross 90 section area compared with the large surface presented, and therefore will prevent the passage of flame and eliminate the risk of damage from back firing.

As the demand of the engine becomes 95 greater, that is, as a greater quantity of gaseous fuel must be supplied to meet the high engine speeds, the valve (p) will rise higher and higher, uncovering a greater port area for fuel entry into the passage (k') 100 forming with the increased quantity of air which enters from (n) into (o), due to the increased rising position of (m), a gaseous fuel of the requisite richness at all times. It will be seen that the ball valve (h') and 105 port h'' admits of the quick falling or forcing down of the plate (m), but acts to restrain its upward movement to aid in the engine more quickly accelerating by securing thereto a richer mixture for a short in- 110 terval of time.

We claim:—

1. In a carbureter, a multiplicity of fuel passages, means for adjusting the flow through each fuel passage, a discharge member for distributing the fuel in a carbureting chamber, said discharge member being movable to admit varying quantities of air into said mixing chamber, a valve of conical form adapted to be opened by suction, 115 means for limiting the opening movement thereof, said valve closing freely upon back firing from the engine, attenuated passage ways in combination with said valve through which discharge of exploding gases may 120 take place upon said back firing.

2. In a carbureter, a multiplicity of fuel passages, means for adjusting the flow through each fuel passage; a distributor plate for distributing the fuel in a carburet- 130

ing chamber, said distributer plate formed with a slidable surface engaging to cover or uncover more or less of the discharge area of said fuel passages, a carbureting chamber, said distributer plate being movable to admit varying quantities of air into said carbureting chamber and a valve of conical form adapted to be opened by suction, and adjustable means for limiting the opening movement of said valve and distributer plate.

3. In a carbureter, a multiplicity of fuel passages, means for adjusting the flow through each fuel passage, a discharge member for distributing the fuel in a carbureting chamber, said discharge member being movable to admit varying quantities of air

into said carbureting chamber, a valve of conical form adapted to be opened by suction, means for limiting the opening movement thereof, said valve closing freely upon back firing from the engine, attenuated passage ways in combination with said valve through which discharge of exploding gases may take place upon said back firing and adjustable means for limiting the opening movement of said conical valve and distributer plate.
